UNITED STATES PATENT OFFICE.

ALBERT W. STEVENSON, OF CANANDAIGUA, NEW YORK.

VACUUM-JAR OPENER.

1,361,639.

Specification of Letters Patent.

Patented Dec. 7, 1920.

Application filed November 13, 1918. Serial No. 262,337.

To all whom it may concern:

Be it known that I, ALBERT W. STEVENSON, a citizen of the United States, residing at Canandaigua, in the county of Ontario 5 and State of New York, have invented new and useful Improvements in Vacuum-Jar Openers, of which the following is a specification.

The purpose of the invention is to provide 10 an implement for attaching or removing the caps of preserving jars. The implement is particularly designed for use to raise the jar cap from the rubber sealing band to admit air from the outside into the jar so as to 15 equalize the air pressure both in and outside of the jar after which the cap may be readily removed by the implement. The means for breaking the rubber seal are movable into and out of operative position so 20 that when it is not desired to use the same they may be moved out of the way when the implement may be used for the purpose of turning the jar cap.

To the exact construction in which it is 25 shown and described, the invention is not to be restricted. The right is reserved to make such changes or alterations as the actual reduction to practice may suggest, in so far as 30 such changes or alterations are compatible in spirit with the annexed claim.

In the accompanying drawings:

Figure 1 is a plan view of the improved 35 tool with the seal breaking elements in their operative positions and their inoperative positions shown in dotted lines.

Fig. 2 is a section on the line 2—2 of Fig. 1.

Fig. 3 is a section on the line 3—3 of Fig. 1.

As shown, the invention comprises two 40 combined jaw and handle elements each formed with a semi-circular jaw 1 terminating in the handle 2. The two elements are pivotally connected together by means of a pin or stud 3 which interconnects the two jaws 1 at their ends. On their inner edges 45 the jaw elements are roughened by knurling or corrugating thus providing the gripping faces 4. Pivotally mounted on each jaw 1 adjacent the point where it connects with the handle 2, there is a lever 5 which is disposed in a slot formed in the jaw and carries at its free end a wedge 6 of semi-elliptical 50 shape in plan and of tapering thickness

from its point to its line of juncture with 55 the lever. The levers 5 may be swung on their pivotal connection 8 so that the wedges 6 may be placed over the handles 2 or these levers may be swung back to abut the slanting ends 7 of the slots in which positions the 60 wedges project beyond the gripping edges 4.

In the use of the tool, the wedges 6 are 65 designed to engage underneath of or on top of the rubber sealing band commonly employed in conjunction with preserving jars. 70 In preserving jars which contain fruit there is more or less of vacuum and, if the tool be placed around the jar adjacent the cap so that the wedges 6 may engage the rubber sealing band, the pressure exerted on the 75 handles 2 to force the same toward each other will force the wedges in underneath the cap and thereby raise the same enough to permit the outside air to find its way into the jar, thus equalizing the pressure inside 80 and outside of the jar. After this condition obtains, the levers 5 may be swung back to the position shown in the dotted lines in Fig. 1, and the gripping edges 4 made to 85 engage the periphery of the cap of the jar 90 by pressure exerted on the handles tending to force them toward each other. The imparting of an angular movement to the tool as a whole will then serve to remove the cap of the jar easily.

In attaching the jar cap the tool is intended to be used in the same way as in unscrewing or removing the cap.

The invention having been described what is claimed as new and useful is:

A tool of the character described comprising a pair of combined jaw and handle elements pivotally connected together, and a lever pivotally mounted on the jaw portion of each element, the lever being formed at 95 one end with a laterally projecting wedge member, each jaw portion having an abutment against which the lever may engage to cause the wedges to project beyond the jaws, the levers being swingable to positions over 100 the handle portions of the elements, whereby the device may be used to initially raise the cap of a preserving jar and thereafter remove the same by clamping the cap between the jaw portions of the two said elements.

In testimony whereof I affix my signature.

ALBERT W. STEVENSON.
